UNITED STATES PATENT OFFICE.

RAY C. FAGAN, OF SPANGLER, PENNSYLVANIA.

PRESSURE-FLUCTUATING ALARM FOR MINES.

Application filed October 29, 1924. Serial No. 746,657.

The present invention consists of a pressure fluctuating alarm for mines and has for an object to provide mechanism which will apprise mine officials of reduction of air pressure in the mine so that steps may be taken to restore the air pressure or to withdraw the miners.

Another object of the invention is to provide an apparatus which may be installed at a point remote from the mine, to be free from any disturbances in the latter, and to be at all times in such close proximity to the office personnel of the mine that any appreciable decrease in the air pressure of the mine will be detected.

A further object of the invention is to provide apparatus of very simple construction which will last for an indefinite period of time without any attention or adjustment and will be efficacious in the preservation of life by giving ample warning, both visible and audible, when air pressure in the mine is at the danger point.

Other objects of the invention will be apparent from the following description of the present preferred form of the invention taken in connection with the accompanying drawing wherein:—

Fig. 1 is a side elevational view of apparatus constructed in accordance with the present invention;

Fig. 2 is a top plan view of the same;

Fig. 3 is a similar view showing the top of the diaphragm casing removed;

Fig. 4 is a fragmentary cross sectional view of the diaphragm casing illustrating the manner in which the diaphragm is mounted therein; and

Fig. 5 is a diagrammatical view of the complete system embodying the signals and electrical circuit which is closed by the diaphragm to operate the signals under predetermined conditions.

It is well known in present day coal mines to regulate the ventilation of the mine through the medium of fans or the like which either force air into the mine through the intake opening of the mine or else withdraw it from the mine through the so-called return opening of the mine. In this way the mine is ventilated either through the medium of the so-called air pressure system, where the first of the two methods above mentioned is followed, or else by the vacuum system, where the latter of the two methods above stated is employed. It has been found

to be difficult to determine when the air pressure in the mine is decreasing to a point of danger to the occupants of the mine, when the air pressure system of ventilation is employed. Conversely, it has been found to be difficult to determine when the vacuum is being relieved in the mine, when the vacuum system of ventilation is employed, with disastrous results. Furthermore, it frequently happens that the air intake and return ways freeze up in the winter time with the result that the mine is cut off from ventilation which causes, at times, gas explosions with manifest consequences. It is customary in many mines to employ the air pressure system of ventilation during the day and the vacuum method of ventilation at night, which has been found more practical in preventing the freezing over of the air ways. The device of the present invention has been so constructed that it is equally adaptable for use on either method of ventilating the mine and will be positive in its operation to give timely warning of any fluctuation of air pressure in the mine.

The apparatus employed in the present invention consists especially of a diaphragm casing 6 which in the present instance is shown to be of rectangular configuration and may be made of wood, metal or other suitable material. A corrugated wafer type of diaphragm 7 is mounted in the casing 6 and embodies a base plate or disk 8 having a central opening which communicates with a right angle way 9 formed in a spool 10 which is secured to the plate 8 and likewise to the diaphragm casing 6. The way 9 is in communication with a pipe 11 which is detachably mounted in the spool 10, said pipe being extended through one wall of the casing 6 and adapted to lead into the mine so that air in the latter is induced into the diaphragm body 7. The outer plate or disk of the diaphragm is adapted for engagement with one end of rod 12, the opposite end of the latter extending through the outer wall of the diaphragm casing and being equipped with a yoke 13 in which a lever 14 made of insulating material, such as fibre or rubber, is pivotally mounted.

The outer wall of the casing 6 is removable and has a pair of plates 15 mounted thereon between which one end of the bar 14 is pivotally mounted, as indicated at 16. The plates 15 are equipped on their inner faces with insulated blocks 17 made of fibre

or similar insulating material upon which contact plates are mounted. One of the contact plates, numbered 18, is relatively long while the other contact plate, numbered 19, is relatively short. These plates are preferably made of brass or like high conductive metal and are arranged to be diametrically opposite with the contact 19 arranged to lie approximately midway the ends of the plate 18. The contact 18 is engaged by a circuit wire 20 which leads to a visible signal, such as a lamp, 21. The contact 19 has a circuit wire 22 leading therefrom which extends to and is engaged with an audible signal such as a bell 23. The lever 14 has a spindle 24 extended transversely therethrough and provided with a pair of terminal brushes 25 which are adapted for engagement with the contacts 18 and 19 when the lever 14 moves inwardly between the plates 15. The spindle 24 is engaged by a circuit wire 26 which leads to a source of electric energy such, for instance, as a battery 27, so that as soon as one of the brushes 25 comes into engagement with either of the contacts 18 or 19 the signals, which are in circuit with the latter, will be operated.

Air pressure within the diaphragm 7 causes the latter to be flexed outwardly and hence urges the rod 12 outwardly so as to hold the lever 14 in a position which will prevent engagement of the brushes 25 with the contacts 18 and 19. When the lever 14 is in the position shown by full lines in Fig. 1, the brush on the side of the contact 18 is spaced only a short distance from the latter so that a slight movement of the lever 14 will cause the brush 25 and contact 18 to engage, and light the lamp 21. It is, consequently, necessary to provide means which will urge the lever 14 inwardly to engage the brushes with the contacts when the pressure in the diaphragm is reduced permitting contraction of the latter. The means employed to effect this result may be a coil spring, such as is shown at 28, one end thereof being engaged with the lever 14 and the opposite end engaged with an adjusting bolt 29 which is detachably mounted in a frame 30. The frame 30 is adapted to be detachably mounted on the outer face of the diaphragm casting 6 as illustrated in Figs. 1 and 2 of the drawings. By making the bolt adjustable the tension of the spring 28 may be correspondingly adjusted so as to assure expeditious and complete movement of the lever 14 when the diaphragm 7 is contracted.

When the vacuum system of ventilation is employed the position of the lever 14 will be substantially as shown by the dotted lines in Fig. 1, under which condition the diaphragm is completely collapsed. As soon as pressure is exerted on the diaphragm by entrance of air through the pipe 11 the diaphragm expands so as to correspondingly

move the lever 14. As soon as the lever moves a very short distance, one of the brushes 25 will contact with the inner end of the contact plate 18 to light the lamp 21. As the lever moves further outwardly the brush will impinge against the contact plate 19 to ring the bell 23.

From the above it is believed to be apparent that so long as the air pressure in the mine is constant the diaphragm will be held in a predetermined position to retain the lever 14 from movement and hold the brushes 25 disengaged from the contacts 18 and 19. Just as soon, however, as the air pressure in the mine fluctuates, the lever 14 will be permitted to move under the influence of the spring until one of the brushes 25 primarily impinges against the contact 18 to light the lamp 21. This gives the first warning to the officials or personnel of the mine office or other place in which this apparatus is installed, that the air pressure in the mine is fluctuating. This affords opportunity to adjust ventilating conditions in the mine and for withdrawing the miners from the mine, if this precaution is deemed necessary. If, however, the air pressure is not restored, the lever 14 will continue to move until the other brush 25 engages the contact 19 thereby operating the audible signal 23. In this way, the mine personnel is adequately warned of the dangerous condition on the interior of the mine so that remedial action may be taken by them to preserve the lives of the persons located in the mine.

It is of course to be understood that I have above described simply a preferred form of my invention and I am aware that numerous changes may be made in the device, and that it may be used in different ways from the one herein recited. Numerous changes may be made in the details of construction, proportion and arrangement of parts within the scope of the claims hereinafter appended.

What is claimed is:—

1. In a pressure-fluctuating alarm, a circuit closer comprising a pair of relatively long and short contacts disposed oppositely to each other and arranged so that the short contact is approximately midway the ends of the long contact, a switch arm pivotally mounted for reciprocation between the said contacts and having brushes adapted for engagement with the contacts when the said arm is moved inwardly between the contacts, and means for moving the switch arm inwardly between the said contacts.

2. In a pressure-fluctuating alarm, a circuit closer comprising a switch arm pivotally mounted at one end, contacts arranged on opposite sides of the said arm, brushes on the said arm adapted to engage the contacts when the arm is moved inwardly be-

tween the latter, a rod connected to the said arm, an expansible diaphragm connected with said rod and adapted when expanded to hold the switch arm positioned with the 5 brushes disengaged from the contacts, and means to urge the arm inwardly between the contacts to engage the brushes therewith when the pressure in the diaphragm is reduced.

3. In a pressure-fluctuating alarm, a circuit closer comprising a casing, a pair of supporting plates on the outer wall of the casing, each of said plates having a contact element on its inner face, a switch arm having one end pivotally supported between 15

said plates, a frame mounted on the outer wall of the casing adjacent the free end of the switch arm, a tensioning spring having one end attached to the frame and the other end to the free end of the switch arm, contact brushes on the said switch arm for engaging the said contacts of the said plates when the arm is reciprocated therebetween, an expansible diaphragm within the said casing and having a pressure-inlet, and a rod 20 having one end connected to the diaphragm and the other end connected with the switch arm.

In testimony whereof I affix my signature.
RAY C. FAGAN.
